UNITED STATES PATENT OFFICE.

JOHN TILL, OF CANTON, PENNSYLVANIA.

PRINTING-PRESS.

SPECIFICATION forming part of Letters Patent No. 237,067, dated January 25, 1881.

Application filed August 30, 1880. (Model.)

To all whom it may concern:

Be it known that I, JOHN TILL, of Canton, in the county of Bradford and State of Pennsylvania, have invented a new and Improved 5 Printing-Press, of which the following is a specification.

The object of this invention is to construct a cheap and simple printing-press, designed especially with a view to easy, rapid, and accurate work.

The invention consists of a four-sided rotary frisket-frame that revolves one-quarter of its circumference for each impression that is made by and between the rocking-bed and platen; 15 and it consists, further, of certain other novel points in the construction and arrangement of parts, all of which are herein fully described.

Figure 1 is a plan view of the device. Fig. 2 is a side elevation of the same with bed and platen fully apart. Fig. 3 is a sectional side elevation of the same on line xx , Fig. 1, showing the position of the parts when an impression is being made. Fig. 4 is a sectional elevation on line yy , Fig. 2. Fig. 5 is a detail elevation intended to show the platen supported by one arm.

Similar letters of reference indicate corresponding parts.

In the accompanying drawings, A represents 30 a suitable frame. B is the bed, rocking on a shaft at b , so as to come in parallelism with the movable platen C when an impression is about to be given. The platen C is supported by a single upright arm, which rocks on the 35 pivots $c c$, and is forced forward by the cam D, that is fixed on the shaft E, and said platen C is retracted by the spring F, whose other end is made fast to a transverse rod, d , of the frame A, as shown. By Fig. 5 of the drawings it will 40 be seen that the platen C is supported by an arm only on one side, to allow for the movement of the frisket-frame without obstruction.

On the projecting end of the shaft E is keyed 45 the cog-wheel E', that gears into the driving cog-wheel G, that is secured on a stud, G', on a side of the frame A, and said wheel E' is provided with an eccentric wrist-pin, f . On the opposite end of shaft E is keyed a disk or wheel, H, provided with an eccentric or wrist-pin, g . From these wrist-pins $f g$ the connecting-rods I I extend to the lateral lugs h of the

bed B, so that at each revolution of the main shaft E platen C and bed B are moved toward each other to make one impression upon the sheet that may be on the frisket that is between them; and it will be seen that when the bed B and platen C are most closely approached to each other the said platen C is immovably held in that position by the cam D for a sufficient length of time to insure a good impression. 55 60

K represents the frisket-frame, consisting of the end plate, K², that revolves in a vertical plane, and of the friskets K', that are removably secured at one end to the plate K² by the nuts l or other suitable device. 65

Secured on the outer face of the end plate, K², is a plate, L, having four equidistant peripheral notches, m , for the reception of the corresponding end of the spring-bolt L', that moves vertically in lugs $m' n'$ that are secured to the 70 frame A, the function of said spring-bolt L' being to hold the frisket-frame K in position when an impression is being made.

On the outer face of the plate L a ratchet, M, is secured, containing four teeth, as shown; and 75 secured loosely on the shaft E, and in face contact with the ratchet M, is an outer circular plate, N, at the periphery of which is a stud, n' , carrying a pawl, n , which latter is designed to engage with teeth of the ratchet M. 80

Connecting the bed B with the plate N, and thereby giving motion thereto, is a connecting-rod, O, having one end slotted, as shown at 85 o , so as to slide on the stud p on the said plate N.

Were the frisket-frame K to move synchronously with the bed B, the angles of the said frame K would be caught between the bed B and platen C before the two latter were sufficiently apart; hence the slot o is formed in the rod O to permit the frisket-frame K to rest 90 until the bed B has been far enough removed from the platen C to allow the frame K to move without interference between said bed and platen B C.

The frisket-arms P are secured, by set-screws 95 or other suitable device, on the rods P', that extend at right angles through the end plate, K²; and on the outer ends of these rods P' are spiral springs P², whose function is to cause the said arms P to hold the sheets to be printed 100 upon the said friskets K'; and upon the outer end of each rod P' is secured, by set-screw or

otherwise, a cam, Q, whose functions are hereinafter described.

Q' represents studs designed for the contact of the cams Q during the operation of the press.

5 R represents the feeding-table, and S the inclined delivery-slide.

Each frisket K' has a covering, k, of silk, muslin, or other suitable fabric, to support the sheets that are to be printed.

- 10 The parts being in the position shown in Fig. 3 and the press being in operation, a sheet is fed from the table R upon the upper frisket, K', and as the frisket-frame K revolves the cam Q, that holds the upper frisket, K', open by its contact with the upper stud, Q', breaks contact with said stud Q' and permits a spring, P², to close the corresponding frisket-arm P down upon the said sheet and hold it there until said frisket-frame K has made three-quarters of a revolution, when the said cam Q comes in contact with the rearmost and lower stud, Q', and thereby the said frisket-arms P are raised, as shown, to permit the escape of the printed sheet from the said frisket K', and thus the work progresses, four sheets being printed at each revolution of the frisket-frame K. On each closing motion of the bed B the connecting-rod O causes the plate N to rotate backward for a quarter of a revolution, 20 so as to disengage the pawl n from the ratchet M and give it a hold in the next tooth, and by this means the friskets K' are successively brought between the bed and platen B C.

When for any purpose it is desired to get at the platen, one of the friskets K' may be removed, and the pawl n may be, if desired, thrown rearward out of gear, so that said frisket-frame K will not rotate, in which case the press may be used as an ordinary press without rotating friskets.

Having thus described my invention, I claim as new and desire to secure by Letters Patent—

1. An improved printing-press constructed substantially as herein shown and described, 45 containing the following elements: frame, vertical rocking bed, cam and spring actuated vertical platen, rotary frisket-frame, and ratchet-and-pawl device for rotating the friskets, combined by mechanism, as set forth.

2. In a printing-press, the combination, with the movable bed B, revolving frisket-frame K, plates L N, ratchet and pawl M n, and stud p, of the slotted connecting-rod O, substantially as herein shown and described, whereby the 55 said frisket-frame is permitted to rest until the said bed is far enough removed from the platen to allow the said frisket-frame to move without interference between said bed and platen, as set forth.

JOHN TILL.
